[57] CLAIM

The ornamental design for an adhesive bandage backing, as shown and described.

DESCRIPTION

FIG. 1 is a perspective view of an adhesive bandage backing showing my new design;

FIG. 2 is a top plan view thereof;

FIG. 3 is a bottom plan view thereof;

FIG. 4 is a front view thereof;

FIG. 5 is a back view thereof;

FIG. 6 is a side view thereof; and,

FIG. 7 is a side view thereof, opposite that shown in FIG. 6. The broken lines shown in FIGS. 3 through 7 are for illustrative purposes only and do not form part of the claimed design.
